US00D753586S

(12) **United States Design Patent**
Fujimoto et al.

(10) **Patent No.:** **US D753,586 S**
(45) **Date of Patent:** **** Apr. 12, 2016**

(54) **LEAD-ACID BATTERY**

(71) Applicant: **GS Yuasa International Ltd.**, Kyoto (JP)

(72) Inventors: **Naoki Fujimoto**, Kyoto (JP); **Sosuke Fujita**, Kyoto (JP)

(73) Assignee: **GS Yuasa International Ltd.**, Kyoto (JP)

(**) Term: **14 Years**

(21) Appl. No.: **29/494,451**

(22) Filed: **Jun. 20, 2014**

(30) **Foreign Application Priority Data**

Dec. 24, 2013 (JP) 2013-030201

(51) **LOC (10) Cl.** **13-02**

(57) **CLAIM**

The ornamental design for a lead-acid battery, as shown and described.

DESCRIPTION

FIG. 1 is a front, top, and right side perspective view of a lead-acid battery showing our new design;

FIG. 2 is a rear, top, and left side perspective view thereof;

FIG. 3 is a front view thereof;

FIG. 4 is a rear view thereof;

FIG. 5 is a top view thereof;

FIG. 6 is a bottom view thereof;

FIG. 7 is a right side view thereof; and,

FIG. 8 is a left side view thereof.

The broken lines shown in the figures are included for the purpose of illustrating portions of the lead-acid battery that form no part of the claimed design.

1 Claim, 8 Drawing Sheets
